UNITED STATES PATENT OFFICE.

SCOTT H. HULL, OF OSKALOOSA, IOWA.

DESIGN FOR A LAWN-SPRINKLER.

SPECIFICATION forming part of Design No. 35,073, dated September 10, 1901.

Application filed August 1, 1901. Serial No. 70,560. Term of patent 3½ years

To all whom it may concern:

Be it known that I, SCOTT H. HULL, a citizen of the United States, residing at Oskaloosa, in the county of Mahaska and State of Iowa, have invented and produced a new and original Design for Lawn-Sprinklers; and I do hereby declare the following to be a full, clear, and exact description of the invention, such as will enable others skilled in the art to which it appertains to make and use the same.

This invention has relation to a design of unique and novel outline for a lawn-sprinkler.

In the drawings, Figure 1 is a side elevation of my design. Fig. 2 is a top plan view, and Fig. 3 is a central section, of the same.

The essential features of the design consist of a circular base provided on its inner diameter with a series of spiral ribs and depressions of approximately V form in cross-section. A ball is mounted on the base, and intermediate the base and ball is arranged a series of ornamental horizontal ridges, and the upper part of the ball is provided with a series of uniquely-arranged perforations or holes. The base 1 has a series of vertically-inclined lines 2 around the outer edge, and a rounded portion 3 extends upwardly from said base, the

rounded portion 3 being of smaller diameter than the base 1. A reduced neck 4 merges from the portion 3, as at 5, and then gradually turns out, as at 6, from whence a flange 8 extends up and joins onto an outwardly-flaring surface 9, and from this surface a ball 10 radiates, the ball being of larger diameter than the surface 9. The ball is made attractive at its upper end by a series of perforations 11, said perforations being disposed intermediate each other to give a pleasing effect. The inner diameter of the base 1 and the portion 3 has a series of spiral ribs and 35 depressions 12 of substantially V form in cross-section, and at the upper end of the spirals is a horizontal flange 13.

Having thus described the invention, what I claim as new is—

The design for a lawn-sprinkler, substantially as herein shown and described.

In testimony whereof I affix my signature in presence of two witnesses.

SCOTT H. HULL. [L. S.]
